UNITED STATES PATENT OFFICE.

THOMAS B. BOMAR, OF FORT WORTH, TEXAS.

COLLAPSIBLE CARRYING-CRATE.

1,216,058.

Specification of Letters Patent.

Patented Feb. 13, 1917.

Application filed November 15, 1915. Serial No. 61,647.

To all whom it may concern:

Be it known that I, THOMAS B. BOMAR, a citizen of the United States, residing at Fort Worth, in the county of Tarrant and 5 State of Texas, have invented a new and useful Collapsible Carrying-Crate, of which the following is a specification.

The present invention appertains to crates and boxes, and aims to provide a novel and 10 improved folding container which may be constructed for shipping or carrying poultry, eggs, bread, and other commodities.

It is the object of the invention to provide a crate, the bottom, top, sides and ends of 15 which fold together in a compact and desirable manner, whereby the crate can be returned in a compact condition and with minimum expense, the crate being readily unfolded for receiving the commodities 20 which are to be transported.

It is also within the scope of the invention to provide a collapsible crate which is comparatively simple, durable, strong and inexpensive in construction, as well as being convenient, practical and efficient in use.

With the foregoing and other objects in view which will appear as the description proceeds, the invention resides in the combination and arrangement of parts and in the 30 details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a perspective view of the crate in unfolded or erected position.

Fig. 2 is a side elevation of the crate, portions being broken away and shown in section.

Fig. 3 is a perspective view of the crate in collapsed condition.

Fig. 4 is a longitudinal section of the crate in folded position.

Fig. 5 is a cross section on the line 5—5 of Fig. 4.

Fig. 6 is a fragmental plan view of one 50 corner of the crate in folded position.

The crate, which may be constructed in various sizes and proportions, according to the use to which it is put, embodies a rectangular bottom 1 having a marginal upturned 55 rim or flange 2.

The ends 3 of the crate are adapted to

set on edge upon the ends of the rim 2, and straps 4 are secured to the inner surfaces of the ends 3 and project downwardly below the lower edges of said ends, as seen in Fig. 60 2, the lower ends of said straps 4 having eyes or hinge butts 5 pivotally embracing cross rods 6 terminally engaged through the side portions of the rim 2 adjacent the ends thereof, or within the end corners of the 65 bottom. The tray-like bottom 1 is sufficiently deep and long that when the ends 3 are swung toward one another and downwardly, they will be received within the rim 2. When the ends 3 are swung up- 70 wardly and away from one another, they seat upon the ends of the rim 2.

The top 7 of the crate is provided with a rectangular rim or frame 8, the ends of which are adapted to sit upon the upper 75 edges of the ends 3, whereby the top is supported firmly, thus enabling a number of the crates to be stacked one upon the other, each crate being capable of withstanding the weight imposed thereon. The rim 8 is of the 80 same size and shape as the rim 2.

The top 7 and ends 3 are connected together, and to this end four links 9 have their upper ends pivoted, as at 10, to the inner surfaces of the side bars of the rim 8 85 spaced from the ends of said rim 8, and the lower ends of said links 9 are pivoted, as at 11, to the upright edges of the ends 3 between the upper and lower edges of said ends. When the ends 3 are swung into position, with the top resting upon said ends, the links 9 are arranged obliquely to act as braces for strengthening the crate. When the ends 3 are swung inwardly and downwardly against the bottom, the links 9 being swung into alinement with the ends 3, will slightly raise the top 7, and the ends 3 in moving downwardly will swing the lower ends of the links 9 inwardly, thereby pulling or drawing the top 7 downwardly with the ends, so that the top will rest upon the rim 2 of the bottom over the folded ends. Conversely, when the top is raised, the links 9 will pull the ends 3 upwardly, to start them into erect position, and said ends can 100 then be readily moved into place under the ends of the top and onto the ends of the bottom.

The sides 12 of the crate are normally disposed snugly between the ends 3, and have attached to their upright edges or ends straps 13 which have their upper ends piv-

oted, as at 14, to the ends of the rim 8 adjacent the side bars thereof, whereby the sides 12 can be swung inwardly and upwardly against the top within the rim 8 thereof. When the sides or side walls 12 are swung into place, they rest against the links 9, and when the sides are swung against the top, the ends 3 can be swung inwardly and downwardly to collapse the 10 crate, the sides moving onto the ends, and the top moving downwardly onto the sides and bottom. It is thus an easy matter to compactly fold the crate for return shipment, and the crate may be readily unfolded 15 to receive the commodities which are to be transported.

As illustrated, the sides, ends and top are provided with meshed wire panels, whereby the crate is particularly useful for shipping poultry, although it is to be understood that the side and end walls and top can be provided with closed panels when the 20 crate is used for shipping eggs, bread, etc.

In order to hold the lower edges of the 25 sides 12 in place when the sides are swung downwardly from the top, the sides 12 are provided with suitable catches 15 adjacent their lower edges which are engageable with keepers 16 carried by the side portions of 30 the rim 2 of the bottom, said catches being of any suitable character. The catches 15 can be readily released when the crate is to be collapsed.

In order to hold the crate in collapsed 35 condition, catches or latches are carried by the bottom and are engageable with the top to hold the bottom and top assembled, whereby they cannot be separated accidentally during the shipment of the collapsed 40 crate. The said catches embody rods 17 disposed slidably within staples or eyes 18 attached to the ends of the rim 2, each rod 17 having a crank 19 at one end, and an angularly extending lug 20 at its other end. 45 The lug 20 prevents the withdrawal of the rod 17 from the staples 18, and the crank 19 provides means for engaging the staple or keeper 21 attached to the respective end of the rim 8. When the crate is folded, the 50 rods 17 can be slid to project the terminals of its cranks 19 through the staples 21 for holding the top and bottom together, and said rods can be readily slid by hand to re-

lease the catches from the staples or keepers 55 21 when the crate is to be unfolded.

The present crate is valuable for shipping various commodities, the crate being adaptable to various uses and being rigid and firm when erected. Furthermore, the 60 crate may be compactly folded and returned with minimum expense.

When the crate is lifted by the top thereof, the braces or links 9 will tend to pull the ends of the crate inwardly, thereby moving them tightly against the sides, and providing a rigid structure. When the crate is folded, as illustrated in Fig. 4, it will be noted that there is a space between the bottom and the sides and ends, so that any dirt or foreign matter that should be left in the 70 crate after it is returned, will not lie upon the top, sides and ends, and can be readily dumped from the bottom. When the device is used as an egg box or crate, the partitions or fillers can be stored within the 75 space provided when the crate is folded.

Having thus described the invention, what is claimed as new is:

A collapsible crate embodying a bottom having an upwardly projecting marginal 80 rim, ends seatable upon the end portions of said rim, downwardly projecting portions carried by the inner surfaces of the ends hinged to the bottom so that the ends can swing within said rim, a top embodying a 85 rim whose end portions are seatable upon said ends when they are swung upwardly, links having their upper ends pivoted to the inner surfaces of the side members of said rim of the top spaced from the ends 90 of the top, the lower ends of said links being pivoted to the upright edges of the ends between the upper and lower edges thereof, and sides hinged within the rim of the top to swing against the top within its rim, 95 the sides being swingable downwardly between the ends, the rim of the top being seatable on the rim of the bottom when the crate is collapsed.

In testimony that I claim the foregoing 100 as my own, I have hereto affixed my signature in the presence of two witnesses.

THOMAS B. BOMAR.
